UNITED STATES PATENT OFFICE.

GERALD ROUTLEDGE, OF OAKLAND, AND AXEL O. NORLING, OF ALAMEDA, CALIFORNIA, ASSIGNORS TO HUTCHINSON CO., OF OAKLAND, CALIFORNIA, A CORPORATION.

CONCRETE MIXER.

Application filed May 14, 1928. Serial No. 277,775.

This invention relates to improvements in concrete mixers generally and in particular to improvements in screw conveyers for such mixers.

5 Concrete mixers of ordinary construction comprise a revoluble drum having a centrally disposed stationary water supply pipe about which the drum rotates. This pipe has a section extending into the drum body and is provided with a plurality of perforations through which the water is forced to the drum interior to be combined with the contents thereof by the revolving action of the drum.

10 Due to the clogging of these perforations by particles of cement, sand, and small stones contained in the mixer, it is often impossible to force sufficient water through these perforations and into the contents of the drum, which causes improper mixing of the contents 15 and the consequent shutting down of the machine until the drum supply pipe can be cleaned.

Our improved device consists of a small screw conveyer secured at one end to the interior wall of the mixing drum and adapted to revolve therewith with its free end projecting into the stationary water supply pipe in such manner that the interior of said pipe will be kept clear of all foreign matter which may 20 enter by ways of the pipe perforations, the perforations themselves being also kept clear and the water in the pipe thus kept flowing freely the full length thereof, thereby causing an even distribution of water to the mix 25 within the revolving drum.

The primary object of our invention is the provision of improved conveyer means adapted for positioning in the water supply pipe of a concrete mixer drum and for rotation with 30 said drum in such manner that the supply pipe will at all times be kept clear of any and all foreign matter which may become lodged in the porforations thereof, thus tending to provide for even and proper distribution of water to the mix at all times.

Another object of our invention is to provide a simple and efficient conveyer device for concrete mixers which may be easily applied to ordinary forms of mixers and which will 40 function in a positive manner to properly distribute water to the interior thereof to insure continuous and proper operation of the mixing drum.

Other objects and advantages of our invention will be apparent with reference to the

subjoined detailed description taken in connection with the accompanying one sheet of drawings, in which:—

Figure 1 is an axial section illustrating a common form of concrete mixer and showing 60 our improved screw conveyer in position within the water supply pipe of the revolving drum. The view also includes the driving means for the mixer, also its roller supports;

Figure 2 is an enlarged sectional detail 65 showing the mixer end of the screw conveyer and the outer end of the water supply pipe in which it is mounted for rotation relative to such pipe;

Referring with greater particularly to the 70 drawings, the numeral 5 designates the mixer in a general way, which comprises in detail, the usual revoluble drum 6 having interior arranged vanes 7 adapted to agitate the contents of the drum. One end of the drum 6 is 75 provided with the usual cone shaped section 8 and opening 9 and the opposite end is provided with an axial bearing member 10 surrounding the water feed pipe 11. The drum 6 is rotatably mounted upon rollers 12 and 13 80 so which carry its weight so that it may be rotated about the axially disposed pipe 11 which projects into the drum and is held stationary relative thereto in the usual manner.

The drum is provided at its rear end with 85 the usual annularly arranged rack 14 which meshes with a driving pinion 15 carried by the driving mechanism 16, through which means rotation of the mixing drum is accomplished in the usual manner. The supply line 90 17 communicates with the horizontally disposed pipe 11 and both are held rigid and against rotation in any suitable manner not shown.

Our improved conveyer member 18 consists, 95 an elongated screw member 19 mounted in the pipe section 11 and extending throughout its entire length, said screw being preferably formed from a single piece of twisted metal and having a stem 20 at 100 its outer end extending through the cap 21, which forms a bearing therefor, and is rigidly secured to the drum end 4 by means of a spider or the like, 22 having a centrally disposed hub 23 for its reception and to which 105 it is rigidly secured by means of a set screw 24.

When in operation, the drum 6 is rotated about the stationary pipe 11 by the driving means 16, which rotary movement causes the rotation of the spider 22 and screw 19 and 110

the consequent rotation of the screw within the pipe 11. This rotary motion of the screw 19 tends to dislodge particles of cement which may be lodged in the water outlet perforations 25 formed in the pipe 11, and, if any cement or particles of sand or gravel entered the pipe through these perforations, due to the agitation of the mixer in the drum, these will be forced out through said perforations 10 or carried outwardly to the end slot 26 and be discharged through by the action of the screw.

The above described rotary movement of the screw 19 continues as long as the drum 6 is in operation and this continuous motion 15 of the screw causes the agitation of the water column in the pipe 11 and assists in the even distribution of the water to the various perforations 25 arranged the whole length of the pipe 11 and also carries the larger particles 20 of foreign matter to the end slot 26 at which point they are discharged into the mix.

Having thus described our invention, and an embodiment of it, in the full, clear and exact terms required by law, and believing that it comprises novel, useful and valuable improvements in the art to which it pertains, we here state that we do not wish to be limited to the precise construction and arrangement 30 of the several parts, as herein set forth, as the same may be variously modified by a skilled mechanic without departing from the spirit and scope of our invention as defined in the appended claims.

35 What we claim and desire to secure by Letters Patent of the United States, is the following, to wit:—

1. A concrete mixer having a revoluble drum and a water supply pipe and a screw 40 conveyer carried by said drum and extending into said pipe and adapted to facilitate the distribution of water to said drum.

2. A concrete mixer having a revoluble drum, a stationary water supply pipe arranged in said drum, perforations in said pipe through which water is sprayed into the interior of the drum, and means carried by said drum and projecting into said pipe to cause the continued agitation of the wa-

ter column therein to facilitate its distribution to said perforations and to prevent the clogging thereof by particles from the agitated mix in said drum. 50

3. In combination with a concrete mixer having a revoluble drum rotatable about a stationary water supply pipe, of a screw member mounted in said water supply pipe and having one end rigidly connected to said drum and adapted for rotation therewith relative to said supply pipe, perforations carried by said supply pipe and a slot carried by the outer end thereof, and means for rotating said drum and screw member to cause the agitation of the water column in said pipe and the even distribution thereof to the various perforations and the simultaneous dislodgment of particles of cement and gravel therefrom. 60

4. In a device of the class described, a stationary water supply pipe and a mixing drum mounted for rotation thereon, means in the form of a screw carried by one end of said drum and adapted for rotary action in said pipe, discharge perforations arranged in spaced relation throughout the length of said pipe and a slot arranged in one end thereof, and means for rotating said drum and screw to cause the forcing of water along said pipe and through spaced perforations. 70

5. In a device of the class described, a stationary hollow water supply pipe having a cap at one end and connected at its opposite end to a suitable supply source, said pipe being provided with evenly spaced perforations and said cap with a slot, and a screw member extending through said cap and adapted for rotary motion in said pipe to evenly distribute the water column in said pipe to the perforations therein and to cause the discharge through said slot of all foreign particles which may enter said perforations from exterior sources. 80

In testimony that we claim the foregoing we have hereto set our hands this 4th day of May, 1928.

GERALD ROUTLEDGE.
AXEL O. NORLING.
